UNITED STATES PATENT OFFICE.

MIROSLAV STÖHR, OF PRAGUE, CZECHOSLOVAKIA.

STOVE.

Application filed July 27, 1923. Serial No. 654,107.

To all whom it may concern:

Be it known that I, MIROSLAV STÖHR, a citizen of the Republic of Czechoslovakia, residing at Prague, Czechoslovakia, have ⁵ invented certain new and useful Improvements in Stoves, of which the following is a specification.

My invention relates to a slow combustion stove in which the admission of the ¹⁰ combustion air, the admission of additional air, as well as the escape of the smoke can be regulated by means of a single device so as to obtain the desired degree of heating. The invention also relates to a regulating device comprising a drum subdivided ¹⁵ into three chambers and provided with slots and a spindle provided with dampers and passing through the centre of the said drum.

More particularly, the regulating device ²⁰ is a slotted drum divided into three cylindrical chambers, a damper being provided in each chamber. The supply of air is controlled by the damper in the central chamber and the discharge of gases by the dampers in ²⁵ the side chambers. Both the last-mentioned dampers are set at the same angle relatively to the damper in the central chamber and all the dampers are carried on a common spindle rotatably journaled in the drum. A space ³⁰ at the back of a gasifying chamber disposed above the furnace and adjacent to the filling opening is likewise divided into three chambers. The central one of these chambers is in direct communication with the furnace ³⁵ and connected to the air supply through the central chamber of the said drum, while the side chambers of the drum which are closed directly to the furnace may be placed in communication either with the furnace ⁴⁰ or with the flues leading to the chimney through the regulating drum.

A construction of the stove according to my invention is diagrammatically shown, by way of example, in the accompanying drawings, in which Fig. 1 is a vertical section of the stove through the central chamber of the regulating drum; Figs. 2 to 4 are fragmental similar sections with the regulating dampers in different positions; Fig. 5 is a ⁴⁵ horizontal section on line B—B in Fig. 1; Fig. 6 is a horizontal section on line A—A in Fig. 1; Fig. 7 is a vertical section on line C—C of Fig. 6; Fig. 8 is a front elevation of the handle for operating the regulating ⁵⁰ dampers; Fig. 9 is a horizontal section on line D—D in Fig. 7; Fig. 10 is a plan of part

of the stove; Fig. 11 is a vertical section on line E—E in Fig. 12 which is a horizontal section on line F—F in Fig. 11; Figs. 13 and 1^a to 4^a are vertical longitudinal sections ⁶⁰ of the stove through the side chambers of the regulating device; Figs. 14 and 15 are views of the regulating device from two opposite sides; Figs. 16 and 17 show a perspective view of the regulating drum seen from two different sides; and Fig. 18 is a perspective view of the spindle with its dampers ⁶⁵ provided in the regulating drum.

The combustion chamber *f* and a gasifying chamber *g* both having perforated walls, ⁷⁰ are disposed above the grate *R* and are separated from each other by a narrow space *S*. Arches 14 provided between the casing of the stove and the lower portion of the gasifying chamber *g* divide the air entering ⁷⁵ the gasifying chamber from the front.

The gasifying chamber *g* is in direct communication with the flue 30, the upper portion of the wall of which is perforated. Ducts 26 are provided between the outer face ⁸⁰ of the said flue and the casing of the stove, the said ducts opening into the ante-chamber of the gasifying chamber *g*. The space between the back portion of the gasifying chamber *g* and the casing of the stove is divided into three chambers by angular intermediate partitions 31 (Fig. 11). The central chamber 4 is in direct communication with the furnace *f* through a passage 3 ⁸⁵ (Figs. 1 and 11). The side chamber 7 are ⁹⁰ closed against the furnace *f* by the said intermediate partitions at the level of the upper edge of the said furnace.

The casing of the stove is divided into ⁹⁵ chambers and is arranged as follows:

Lower conduits 6^a are disposed symmetrically to the centre (Figs. 11 and 12) and are closed against the ash-pit 32 by partitions 33. Lateral vertical conduits 6^b which extend partially over the front of the casing of the stove passing in front of the gasifying chamber *g* open into the said conduits 6^a into which likewise open conduits 6 provided on the back of the casing of the stove and leading to a horizontal cylindrical casing 34 in communication with an uptake 10 connected to the chimney. The furnace gases thus flow through the said conduits 6, 6^a and 6^b.

Rear ducts 20 and front ducts 15 are provided at the corners of the stove and are in communication with the surrounding air through apertures cut in the casing of the ¹⁰⁵ ¹¹⁰

stove and extending almost to the floor of the latter, so that the said surrounding air has access to the interior of the casing of the stove. These ducts 20 and 15 open into a chamber 23 surrounding the gas-discharging ducts 26 of the filling opening. The top of the chamber 23 is provided with tubes 24 establishing communication between the chamber 23 and a chamber 25 immediately above the latter. The chamber 25 is filled with water and is either in direct communication with the surrounding air through openings in the casing or is provided with a discharge conduit 22.

Atmospheric air has also access to the above-mentioned ducts 20 through a chamber 18 provided on the rear and central lower portion of the casing of the stove (Fig. 1). This chamber 18 is in communication with atmospheric air through a conduit 17 and has on both sides conduits 19 leading to the ducts 20. A passage 35 opens into the cover of the chamber 18 and also leads to a central slot in the cylindrical casing 34 which contains a drum *r* (Figs. 16 and 17) closed at each end at 36 and having intermediate partitions 37 whereby the drum is divided into a central chamber 38 and two side chambers 39 respectively. The drum *r* is axially traversed by a rotatably journaled spindle 40 carrying a damper *v* in the chamber 38 and a damper *k* in each of the chambers 39, the dampers *k* being arranged to both form the same angle with the central damper *v*. The spindle 40 projects externally from the casing 34 and may be rotated by means of a handle 41 for the purpose of setting the dampers in various positions.

The division of the drum *r* into the chambers 38 and 39 corresponds to the arrangement of the chambers 4 and 7 at the back of the gasifying chamber *g*. The wall of the drum *r* has suitable slots adapted to cooperate with apertures in the casing 34 in which the drum is mounted.

Referring to Fig. 4, the portion of the wall of the drum *r* facing the interior of the stove has a slot 2 occupying the width of the central chamber 38 of the drum *r* and lying below a horizontal plane passing through the axis of the drum. Each of the side chambers 39 of the drum has a similar slot 5. Further slots 8 are provided on the wall of the chambers 39 above the said central plane and above the slots 5, so that free passage is afforded through the slots 5, the chambers 39 and the slots 8 when the dampers *k* are in the correct position.

Referring to Figs. 15, 16 and 17, the rear wall of the regulating drum *r* has slots 1^a, 1^b, 1^c occupying the width of the central chamber 38 and lying below the above-mentioned central plane. Each of the chambers 39 has similar slots 9 and 11, the slots

11 extending somewhat above the said central plane. Finally, a further slot 12, occupying the width of the chamber 38, is positioned above the slots 1^a, 1^b and 1^c and above the said central plane of the drum *r*.

70

The essential point is that the combustion air should pass directly only into the lower portion of the furnace chamber *f*, and the spreading of the air towards the upper part of the stove gasifying chamber *g* be brought about by the draft of the chimney.

75

Accordingly each of the chambers of the drum *r* and all these chambers are simultaneously regulated as regards their relation to the stove chambers and flues by means of the dampers *k*, *v* which can be rotated with the spindle 40 in any direction.

80

The heating and ventilation of the room are regulated in the following manner:

With the regulation effected in accordance with Figs. 1 and 1^a, the incoming air passes through the slots 1^a and 1^b into the central chamber 38 of the regulating drum *r* below the damper *v* whence the air passes only through the slot 2 owing to the position of the damper *v*, and reaches the lower portion of the furnace chamber *f*.

90

The air passes also through the passage 3 into the chamber 4 in which it is heated and thence into the gasifying chamber *g* where it becomes mixed with the combustion gases and causes them to burn completely. The chimney draft acts on the furnace and gasifying chamber of the stove through the uptake 10, the slots 9 in the chambers 39 of the regulating drum *r*, the drum itself and its slots 8. When necessary, and according to the position of the dampers *k*, the air can also be caused to pass from the ante-chamber of the furnace chamber *f*, through the slots 5, 11, side chambers 39 of the regulating drum *r*, the conduits 6, the lower conduits 6^a adjoining the latter, then through the lateral vertical conduits 6^b into the ante-chamber of the gasifying chamber to the 100

95

gasifying chamber after being heated in the inner flues. Accordingly, the combustion air spreads over the whole upper part of the gasifying chambers *g*. The combustion gases which rise in the furnace chamber and in the gasifying chamber, in as far as they are not completely burnt by the supply of heated combustion air, collect with the smoke and other material in the side chambers 7 and pass through the slots 8, the regulating drum *r* and its slots 9, into the uptake 10. The gases generated in the filling chamber above the gasifying chamber, pass through the openings of the filling duct into the conduits 26 arranged round the filling duct and opening into the ante-chamber of the gasifying chamber *g* (Figs. 1 and 1^a).

110

If after this setting of elements which is done to start or light the stove, the fire is to burn constantly at a high rate, the regulating 125

120

130

dampers k , v are turned into the position shown in Figs. 2, 2^a and 13. The path for the admission of air and the action of the said air remains the same. On the contrary, the furnace chamber f is connected directly through the slots 5 and 8 of the regulating drum with the chambers 7 in which gases collected in the previous position of the said drum, so that the heated combustion air escaping from the chamber 7, together with the air also heated which escapes in the same direction from the chamber 4, cause a complete combustion of the combustion gases in the whole of the gasifying chamber g . The discharge of the combustion gases into the chimney takes place however exclusively through the flues 6^b, 6^a, 6 (Fig. 13) as well as through the side chambers 39 of the drum r , provided with the slots 11 and 9, whereby a considerable heating of the floor is produced.

The action of the furnace, with the dampers k , v in the position shown in Figs. 3 and 3^a, is reduced while the quantity of the air supplied is halved. The excess of air passes directly into the chimney through the slot 1^a, the regulating drum r and slot 12 so that the whole room is ventilated. The discharge of the combustion gases remains the same.

With the dampers k , v in the position shown in Figs. 4 and 4^a, the admission of air is completely shut off. The ventilation of the room is considerably increased by the air current through the slots 1^a, 1^b, 12. The discharge of the combustion gases from the stove, reduced to a minimum by the ventilating current of air, as well as the discharge of the secondary air from the ante-chamber 10 of the furnace f and chamber 4, into the uptake 10 which is throttled takes place through the flues 6^b, 6^a, 6 and slots 11 and 9.

In that way, by turning the spindle 40 carrying the dampers k , v in one or the other direction, it is always possible to ensure the desired degree of heating.

In order to bring about circulation, purification and moistening of the air of the room, the air admitted passes through the

conduits 1^c and 17, chamber 18, and ducts 20 and 15 (Fig. 1) into the chamber 23 surrounding the upper part of the stove, and from the said chamber through the tubes 24 into the water chamber 25. The cover of the said chamber is cooled by a water tank 27 so that the steam generated in the water in chamber 25 condenses on coming in contact with the cover, and drops down in the form of a fine spray. The air passing in fine jets through the said spray, is therefore purified and moistened, and in that state passes into the room or may be conveyed elsewhere.

I claim as my invention:

1. In a slow combustion stove, the combination with the furnace- and gasifying chamber and a casing enclosing the same, of a regulating drum having slotted walls and being divided into three chambers, the space between the said gasifying chamber and the rear of the said casing being likewise divided into three chambers, corresponding to the chambers in the said regulating drum, and means in the said regulating drum for connecting the central chamber of the said space directly to the said furnace chamber, and the other chambers in the said space either directly or indirectly to the said gasifying chamber for supplying air to the said chambers.

2. The combination as specified in claim 1, in which the said regulating drum comprises a cylindrical casing provided with slots, a rotatable spindle passing through the center of the said casing and being journaled therein, and dampers carried by the said spindle, one damper in each chamber, the dampers in the two outer chambers of the said casing being offset at the same angle relative to the damper in the central chamber of the said casing.

In testimony whereof I have signed my name to this specification in the presence of two subscribing witnesses.

MIROSLAV STÖHR.
